P. A. MASTEL.
WOOD SPLICING TOOL.
APPLICATION FILED AUG. 4, 1919.

1,367,883.

Patented Feb. 8, 1921.

FIG. 1.

INVENTOR:
Peter A. Mastel.

BY HIS ATTORNEY:

A. M. Carlsen.

UNITED STATES PATENT OFFICE.

PETER A. MASTEL, OF ST. PAUL, MINNESOTA, ASSIGNOR OF ONE-HALF TO BARRETT & BARRETT, OF ST. PAUL, MINNESOTA, A CORPORATION.

WOOD-SPlicing TOOL.

1,367,883.

Specification of Letters Patent.

Patented Feb. 8, 1921.

Application filed August 4, 1919. Serial No. 315,303.

To all whom it may concern:

Be it known that I, PETER A. MASTEL, a citizen of the United States, residing at St. Paul, in the county of Ramsey and State of Minnesota, have invented a new and useful 5 Wood-Splicing Tool, of which the following is a specification.

This invention relates to improvements in tools for splicing wooden parts together. 10 It is especially designed for the splicing of billiard cues when new tip ends are to be substituted for split or worn out tips; but it may also be used for splicing or joining together endwise new parts, or new and old 15 parts of wooden handles, chair legs, flag poles, fence posts, umbrella sticks and many other articles.

In the accompanying drawing: Figure 1 is a partly sectional side view of a billiard 20 cue onto which the front portion has been spliced by my improved tool. Fig. 2 is a side view of the male member of the tool. Fig. 3 is a section on the line 3—3 in Fig. 2.

Referring to the drawing by reference numerals, 5 designates a portion of a billiard 25 cue to which a new front part, 5^x is spliced by a joint composed of an inside cone, 6, formed on the cue and having a shoulder 7, which is preferably underdug some or given 30 a recess, 7^x, and a hollow outside cone, 8, of the front piece 5^x, which is tightly fitted and glued or otherwise secured upon the cone 6.

In order to form said wooden cones quickly 35 and accurately, I provide a special tool composed of a female member (not shown) and a male member; only the latter member will be described and claimed in this case. Said member is provided with a shank, 12^a by 40 which it may be secured in the tail-stock

of a lathe, while the wooden part operated on may be held in a chuck carried by a spindle of the lathe. If the wooden piece is long the spindle is to be of the hollow or tubular type, so that the wood may extend 45 through it. The tool may also be rotated and the wood pushed against it.

The shank 12^a is formed with a tapered two-edged blade 33, having the sharp edges 34 curved or converged at 35 toward the 50 point 36. It also has a longitudinal rib, 37, at each side of it to stiffen it.

Secured upon the front end of the shank 12^a by a screw 38, is a collar 39. Upon the front side of said collar is adjustably secured 55 by a screw 40 a cutter blade 41, having a cutting edge 42 of such form and in such a position that when the tool is in operation to bore the conical hole in the socket 8, by its edges 34—35, said cutter 42 will so form 60 the edge of the socket, that it will fit the shoulder 7 and its recess 7^x of the male cone 6 of the part 5 of the wood.

From the foregoing description it will readily be seen how the tool operates to form 65 the female splice member. After both members are formed they are pressed tightly one into the other and secured either by glue or by a nail 43, or both glue and nails.

What I claim is:

An auger for producing the socket part 70 of a wood splice, said auger comprising a shank with a tapered two-edged blade having a blunt point, a collar fixed on the shank near said blade, and a cutter blade adjustably secured to the front side of the collar and serving to form the edge of the socket formed by the tapered blade.

In testimony whereof I affix my signature.

PETER A. MASTEL.
